DESIGN FOR AN EVENING WRAP

Adolph Brieff, New York, N. Y.

Application June 23, 1938, Serial No. 78,006

Term of patent 3½ years

To all whom it may concern:

Be it known that I, Adolph Brieff, a citizen of the United States of America, residing in New York city, in the Borough of Manhattan, county and State of New York, have invented a new, original, and ornamental Design for an Evening Wrap, of which the following is a specification, reference being had to the accompanying drawing, forming part thereof, wherein,

Figure 1 is a front view of an evening wrap showing my new design.

Figure 2 is a rear view of the evening wrap shown in Figure 1.

The characteristic feature of my design resides in the combination on the front blouse section of the specific evening wrap of the diagonal darts extending downwardly and outwardly from the top of the narrow stand-up collar and the specific girdle across the gathered front thereof, as shown.

I claim:

The ornamental design for an evening wrap, substantially as shown and described.

ADOLPH BRIEFF.
